Primary Examiner — Elizabeth J Oswecki(74) *Attorney, Agent, or Firm* — Banner & Witcoff, Ltd.(57) **CLAIM**

The ornamental design for a shoe, as shown and described.

DESCRIPTION

FIG. 1 is a side photographic view of a shoe showing my new design;

FIG. 2 is a top view thereof; and,

FIG. 3 is a front view thereof.

The remainder of the shoe shown in a greyed out photographic depiction forms no part of the claimed design. The broken lines immediately adjacent to the shaded area represent the bounds of the claimed design and form no part thereof.
